UNITED STATES PATENT OFFICE.

FREDERIC WILLIAMS THOMPSON, OF ATLANTIC CITY, NEW JERSEY.

SHOOTING-GALLERY.

1,256,079.

Specification of Letters Patent. Patented Feb. 12, 1918.

Application filed March 3, 1917. Serial No. 152,216.

To all whom it may concern:

Be it known that I, FREDERIC W. THOMPSON, a citizen of the United States, and a resident of Atlantic City, in the county of Atlantic and State of New Jersey, have invented a new and Improved Shooting-Gallery, of which the following is a full, clear, and exact description.

The object of the invention is to provide 10 a new and improved shooting gallery arranged to require considerable skill on the part of the shooters to hit a distant target.

In order to accomplish the desired result, use is made of a shooter's stand in the form 15 of an aeroplane, a distance target, and mechanical means holding the said shooter's stand suspended in mid-air and imparting a rocking motion thereto. Use is also made of means for detachably suspending the target 20 and carrying the same along in an endless pathway, the target being preferably in the form of a miniature aeroplane.

A practical embodiment of the invention is represented in the accompanying drawings forming a part of this specification, in which similar characters of reference indicate corresponding parts in all the views.

Figure 1 is a sectional perspective view 30 of the shooting gallery;

Fig. 2 is a face view of the target background;

Fig. 3 is a cross section of the target, the endless carrier and the background;

Fig. 4 is a front elevation of the same;

Fig. 5 is an enlarged sectional front elevation of the shooter's stand with the walls of the gallery shown in section; and

Fig. 6 is a cross section of the same.

In the front portion of the gallery 10 is 40 arranged a shooter's stand 11 and in the rear are traveling targets 12 adapted to be shot at by the shooters or gunmen standing on the stand 11. The shooter's stand 11 is preferably in the form of an aeroplane suspended 45 in mid-air and adapted to rock from side to side. The lower wing of the stand forms a floor 13 for the shooters to stand on and steps 14 lead to the end portions of the said floor for the shooters to pass onto the floor 50 13 or to move away from the same at the time the stand 11 is at a standstill.

Various mechanical means may be employed for suspending the shooter's stand 11 and for imparting a rocking thereto, for instance, as shown in the drawings, the floor 55 13 is hung at its ends on upwardly extend-

ing rods 20 connected at their upper ends with the cranks 21 of crank shafts 22 journaled in suitable bearings arranged on brackets 23 attached to an overhead beam 24 60 extending along the ceiling of the gallery 10. The crank shafts 22 are provided with bevel gear wheels 25 in mesh with bevel gear wheels 26 secured on a shaft 27 journaled in suitable bearings arranged on the brackets 23. One end of the shaft 27 (see Figs. 1 and 5) is provided with a bevel gear wheel 28 in mesh with a bevel gear wheel 29 secured on the upper end of a shaft 30 journaled in suitable bearings 31 arranged on the adjacent side wall of the gallery 10. The lower end of the shaft 30 is provided with a bevel gear wheel 32 in mesh with a bevel gear wheel 33 secured on the shaft 34 of an electric or other motor 35 of any approved construction. When the motor 35 is running then a rotary motion is transmitted by the gearing described to the shaft 27 whereby a rotary motion is given to the crank shafts 22 which by their cranks 21 and their links 20 70 impart a sidewise rocking motion to the shooter's stand 11, as will be readily understood by reference to Fig. 5, in which the two cranks 21 are shown in diametrically opposite positions to produce the desired result.

The rear of the stand 11 is provided with propellers 40 driven by a sprocket wheel and sprocket chain mechanisms 41 from a motor 42 mounted on the floor 13, and the 80 propellers are preferably inclosed in a wire netting protector 43, as shown in Fig. 1. When the motor 42 is running a rotary motion is given to the propellers 40 whereby an air current is induced in a lengthwise 95 direction thus giving an aeroplane effect to the shooters standing on the floor as well as to the onlookers in front of the shooting gallery.

Each of the targets 12 is preferably in 100 the form of a miniature aeroplane and is provided on top with an eye 50 detachably engaging the return bent end 51 of a holder 52 in the form of a rod provided with a flanged wheel 53 traveling in an endless slot 105 54 formed in the target background 55 extending across the gallery 10 in the rear of the targets 12. The rear end of each holder 52 is attached to an endless traveling sprocket chain 60 passing around a series 110 of sprocket wheels 61 located in such a position as to guide the sprocket chain 60 along

the slot 54, as will be readily understood by reference to Fig. 2. The sprocket wheels 61 are attached to suitable shafts 63 journaled in a support 64 arranged in the rear 5 of the target background 55. A suitable driving motor 65 is connected with one of the shafts 63 to impart a traveling motion to the chains with a view to carry the target 12 along. The top portion of the slot 54 10 is preferably made undulating so as to give a bodily up and down movement to the targets 12 while traveling along the upper portion of the said slot. Each target 12 is preferably provided with a flat surface 70 15 facing the shooter's stand 11 so that when this surface is struck by a bullet fired from a rifle in the hands of a shooter standing on the stand 11 then the struck target is moved rearward and drops off the return bend 51 20 down onto the floor of the shooting gallery thus signifying that the shooter has hit the target. It will be noticed that the arrangement described simulates an aeroplane battle, and this effect may be heightened by 25 producing a stereoscopic cloud effect on the target background 55. It will also be noticed that as the shooter's stand 11 is continually rocked it requires considerable skill on the part of the shooter on the stand to 30 shoot correctly with a view to hit one of the targets 12.

Having thus described my invention, I claim as new and desire to secure by Letters Patent:—

- 35 1. A shooting gallery, comprising a shooter's stand, mechanical means holding the said shooter's stand suspended and imparting a rocking motion thereto, a distant target, and mechanical means moving the said 40 target in a plane parallel to the plane in which the said shooter's stand is rocked.
- 45 2. A shooting gallery, comprising a shooter's stand mounted to rock sidewise, and a distant target mounted to travel in a plane parallel to the plane in which rocks the said shooter's stand.
- 50 3. A shooting gallery, comprising a shooter's stand, mechanical means holding the said shooter's stand suspended in mid-air and imparting a sidewise rocking motion to the said shooter's stand, a series of distant targets, and mechanical means having traveling holders removably suspending the said targets and moving the said targets in

a plane parallel to the plane in which rocks 55 the said shooter's stand.

4. A shooting gallery, comprising a shooter's stand in the form of an aeroplane having one of its wings forming a floor for the 60 shooters to stand on, mechanical means suspending the said shooter's stand in mid-air and rocking the same, fixed approaches leading to the said floor, distant targets in the form of miniature aeroplanes, and mechanical traveling and suspending means detachably supporting the said targets and carrying the same bodily along.

5. A shooting gallery, comprising a shooter's stand in the form of an aeroplane having one of its wings forming a floor for the 70 shooters to stand on, mechanical means suspending the said shooter's stand in mid-air and rocking the same, fixed approaches leading to the said floor, distant targets in the form of miniature aeroplanes, and mechanical traveling and suspending means 75 detachably supporting the said targets and carrying the same bodily along in a plane parallel to the plane in which the said shooter's stand is rocked.

6. A shooting gallery, comprising a shooter's stand in the form of an aeroplane having one of its wings forming a floor for the 80 shooters to stand on, mechanical means suspending the said shooter's stand in mid-air 85 and rocking the same, fixed approaches leading to the said floor, a target in the form of a miniature aeroplane, and an endless traveling carrier located a distance in front of the said shooter's stand and provided with 90 a holder adapted to removably support the said target.

7. A shooting gallery, comprising a shooter's stand in the form of an aeroplane having one of its wings forming a floor for the 95 shooters to stand on, mechanical means suspending the said shooter's stand in mid-air and rocking the same, fixed approaches leading to the said floor, a target background located a distance in front of the said 100 shooter's stand and provided with an endless slot, a holder extending through the said slot, a target detachably held on the front end of the holder, and a carrier in the rear of the said background and connected with 105 the rear end of the holder to move the latter along in the slot.

FREDERIC WILLIAMS THOMPSON.
